UNITED STATES PATENT OFFICE.

FRANK McDANIELS, OF MINNEAPOLIS, MINNESOTA.

SHADE-CLOTH TRIMMER.

SPECIFICATION forming part of Letters Patent No. 727,667, dated May 12, 1903.

Application filed December 8, 1902. Serial No. 134,223. (No model.)

To all whom it may concern:

Be it known that I, FRANK McDANIELS, of Minneapolis, county of Hennepin, State of Minnesota, have invented certain new and useful Improvements in Shade-Cloth Trimmers, of which the following is a specification.

My invention relates to devices for trimming the ends of window-shades; and the object of the invention is to perfect the device shown and described in Letters Patent of the United States No. 713,333, issued to me November 11, 1902, by providing means operating as an adjunct to the trimming-knives for cutting off the superfluous end of the shade-roll stick.

A further object is to provide means whereby the operator can easily determine the proper amount to be cut from the end of the stick.

Other objects of the invention will appear from the following detailed description.

The invention consists generally in providing a saw in connection with the cloth-trimming mechanism.

Further, the invention consists in providing means for rendering the saw operative or inoperative, as desired; and, further, the invention consists in a suitable gage device by means of which the desired amount to be cut from the end of the stick can be easily and quickly determined.

Further, the invention consists in various constructions and combinations, all as hereinafter described, and particularly pointed out in the claims.

In the accompanying drawings, forming part of this specification, Figure 1 is a plan view of my improved shade-roll trimmer. Fig. 2 is a longitudinal section of the same. Fig. 3 is a transverse section on the line x-x of Fig. 1. Fig. 4 is a view looking at the rear of the trimming mechanism, the supporting-hub for the revolving member being shown in section. Fig. 5 is a vertical section through the cloth-trimming mechanism and the saw. Fig. 6 is a front view of the device, showing the saw and knives projected partially across the opening in the revolving disk. Fig. 7 is a rear view showing the knives and saw retracted. Fig. 8 is a detail sectional view showing the saw in its inoperative position.

Fig. 9 is a front view showing a modified form of saw. Fig. 10 is a vertical section showing the knives and an adjustable saw. Fig. 11 is a detail of the saw, showing the means provided for preventing rotation thereof on its axis.

In the drawings, 2 represents a board; 3, a hub or barrel having a central opening 4 and a lip 5, that extends over the end of the board 2 and is secured thereto by screws or any other suitable means. A gear 6 is provided at the inner end of the hub 3, and a revolving disk or member 7, having an operating-handle 7', is mounted on said hub and held thereon by a ring 8, that is secured to the outer end of said hub and is countersunk in the face of said disk and permits the revolution of the disk on the hub, while preventing their accidental separation. The revolving disk is provided upon each side of the hub-opening with guideways 9, wherein blocks 10 are slidable and normally projected toward the opening 4 by springs 11. Knives 12, having, preferably, V-shaped cutting edges, are mounted on the blocks 10 and are normally held projecting partially across the opening 4 by the yielding pressure of said springs. The blocks 10 are provided also, preferably on the side opposite the knives, with stops 13, having beveled edges 14, that are in position to be engaged by the corresponding faces 15 of lugs 16, provided on a ring 17, that is revolute on the hub of the disk 7 between it and the gear 6. This ring 17 is preferably provided with an operating-handle 18, by means of which the operator can partially rotate said ring, move the beveled faces 15 into engagement with the corresponding faces on the stops 13, separate the knives against the tension of the springs 11, and withdraw them from the opening 4 to allow of insertion of the end of a shade-roll therein. After the insertion of the roll the knives are released by a reverse movement of the lever 18, and the springs will throw the knives into engagement with the shade-cloth. The operator will then revolve the member 7 to perform the trimming operation. All this mechanism, however, is substantially the same as that described in my former patent above referred to, and I

make no claim to the same herein except in combination with the novel features as hereinafter described.

It is desirable after the cloth is trimmed to provide some means for cutting off the end of the stick, which has been usually done by a handsaw not connected with and operating entirely independent of the trimming mechanism. To perfect the trimmer and to render its operation complete, I provide a yoke or frame 19, having a stud 20 on one side fitting within an opening in the revolving disk or member 7, near the circumference thereof. A handle 21 is provided on the yoke 19, and a lug 22 is provided on the stud 20 and normally holds the stud against forward movement, but when opposite a certain predetermined point in its revolution will enter a slot 23 in the revolving member and allow the stud and yoke to be drawn forward, as shown in Fig. 8. A shaft 24 is centrally mounted in said stud and projects forward through the yoke 19 and into said handle, and upon the rear end of this shaft a pinion 25 is mounted in position to engage the teeth of the stationary gear 6 and be moved out of engagement therewith by the forward movement of said stud. A gear 26 is mounted on the shaft 24 within the frame 19, meshing with a pinion 27, mounted on a bolt 28 and carrying a circular saw 29 on its hub.

From the foregoing it is evident that when the member 7 is revolved and the pinion 25 is in engagement with the teeth of the stationary gear said pinion, in addition to its movement around the circumference of said stationary gear, will also revolve with the shaft 24, which in turn will drive the gear 26, the pinion 27, and the circular saw 29. The saw is arranged outside the trimming-knives any suitable distance, preferably about three-eighths of an inch, and during the operation of the knives will be out of gear and inoperative, as shown in Fig. 8. When the saw is not in use, it is swung around out of the path of the shade-roll by the tension of a spring 30, connecting the yoke 19 with the revolving member. (See Figs. 6 and 7.) In the rear of the trimming mechanism upon the board 2 I provide a support or rest 31 for the roll, and along the middle of said board I arrange a plate 32, provided with a scale 33, the board beneath said scale having a recess or slot 34, wherein a gage 35 is movable, being adjustably secured to the plate 32 by a set-screw 36. The marks upon the scale represent inches and feet and will enable the operator by adjusting the gage to very easily and quickly ascertain how much to cut off the end of the stick to obtain the desired width of shade. A plate 37 is preferably secured to the board 2, having a circular socket 38, wherein the end of the shade-stick may be thrust to adjust the edge of the cloth preparatory to trimming.

Instead of using the knives having V-shaped edges, as heretofore described, I may

provide circular knives 39, mounted on pivots 40 between the brackets 41 and the reciprocating blocks 10, these knives having circular cutting edges that engage the cloth to trim the same, and I prefer to provide three of them and a corresponding number of guides 9 and blocks 10 in the revolving disk, as shown in Fig. 9, the radial movement of the blocks and the manner of withdrawing the knives from the shade-roll opening being substantially the same as in the mechanism before described.

The saw and the driving mechanism therefor (shown in Figs. 9 and 10) are the same as those before described; but I prefer to provide a long threaded hub 42 on the pinion 27 and provide a longitudinal slot 43 therein to receive a lug 44, provided on the saw, that will permit adjustment of the saw longitudinally on the hub, but prevent its revolution independently thereof. The saw is locked in any desired position on the hub by means of the lock-nuts 45. By loosening these nuts the saw can be adjusted toward or from the knives and the length of the cut at the end of the stick varied as desired.

The operation, briefly, of my improved shade-trimmer is as follows: The knives having been separated and withdrawn from the hub-opening, the end of the shade-roll is inserted therein, with the opposite end supported upon the rest 31 in a horizontal position. The gage is then adjusted to determine the proper amount to be trimmed, and the knives are then released, allowing them to fly back and engage the cloth. The disk or member carrying the knives is then revolved and the desired amount trimmed from the edge of the cloth. During this time the saw has been out of gear and inoperative. As soon, however, as the cloth is trimmed the saw is thrown into gear, the revolving member set in motion again, and the end of the stick quickly and neatly cut off.

I claim as my invention—

1. The combination, in a shade-cloth trimmer, with a revolving member having an opening to receive the end of a shade-cloth roll, of knives arranged to engage and trim the edge of the cloth, and a stick-trimming saw.

2. A shade-cloth trimmer, comprising a revolving member adapted to receive the end of a shade-cloth roll, cloth-trimming knives carried by said member, and a circular saw also carried by said member.

3. A shade-cloth trimmer, comprising a revolving member adapted to receive the end of a shade-cloth roll, radially-movable knives carried by said member, and a stick-trimming saw also carried by said member.

4. A shade-cloth trimmer, comprising a revolving member adapted to receive the end of a shade-cloth roll, reciprocating knives yieldingly mounted in said member, a saw carried by said member, means for driving said saw, and means for rendering said saw operative or inoperative.

5. A shade-cloth trimmer, comprising a member adapted to receive the ends of a shade-cloth roll, revolving cloth-trimming knives carried by said member and a stick-trimming saw.
6. A shade-cloth trimmer, comprising a member having an opening to receive the end of a shade-cloth roll, and radially-movable circular knives carried by said member and arranged to be projected partially across said opening and a stick-trimming saw, for the purpose specified.
7. A shade-cloth trimmer, comprising a revolving member having an opening to receive a shade-cloth roll, radially-movable circular knives carried by said member and arranged to be projected partially across said opening, and an adjustable stick-trimming saw also carried by said member.
8. A shade-cloth trimmer, comprising a revolving member having an opening to receive the end of a shade-cloth roll, a stick-trimming saw carried by said member, and means for revolving said saw when said member is operated.
9. The combination, with a revolving member adapted to receive the end of a shade-cloth roll, of radially-movable circular knives yieldingly mounted in said member, a circular saw carried by said member near the circumference thereof, and means for driving said saw during the revolution of said member.
10. The combination, with a hub having an opening and a fixed gear, of a disk revolvably mounted on said hub, a series of cloth-trimming knives mounted in said disk, a saw also carried by said disk, and operative means connecting said saw and said gear.
11. The combination, with a hub having an opening to receive the end of a shade-cloth roll and a fixed gear, of a disk or member revolvably mounted on said hub, a stick-trimming saw carried by said disk, and operative connections provided between said saw and said gear.
12. The combination, with a hub having an opening to receive the end of a shade-cloth roll and a fixed gear, of a revolving disk or member mounted on said hub, a gear mechanism carried by said disk and meshing with said fixed gear, means for disconnecting said gear mechanism from said fixed gear, and a circular stick-trimming saw provided in connection with said gear mechanism and operated thereby.
13. The combination, with a hub having a central opening and a fixed gear, of a revolving member mounted thereon, a yoke having a stud pivoted in said member, a shaft carried by said stud and having a pinion meshing with said fixed gear, a gear provided on said shaft, a pinion meshing with said last-named gear and a circular stick-trimming saw carried by said pinion.
14. The combination, with a hub having a central opening and provided with a fixed gear, of a revolving member mounted on said hub, a yoke having a stud pivoted in said member, a lug provided on said stud and adapted to enter a slot in said member and allow longitudinal movement of said stud, a shaft carried by said stud and having a pinion to engage said fixed gear, a gear mounted on said shaft, a pinion engaging said last-named gear, a circular saw carried by said pinion and normally projecting partially across the opening in said hub, and a spring for holding said yoke and saw retracted when inoperative.
15. The combination, with a hub having a central opening, of a board whereon said hub is mounted, a rest provided on said board, a gage-plate arranged upon said board and having a suitable scale, a gage movable over said scale, a revolving member mounted on said hub, cloth-trimming knives carried by said member, and a stick-trimming saw.
16. The combination, with a board, of a hub secured thereon and having a central opening, a scale-plate, a gage provided on said board, a rest also arranged on said board, a revolving member mounted on said hub, radially-movable knives carried by said member and normally projecting partially across the opening in said hub, and a stick-trimming saw.
17. The combination, with a hub adapted to receive the end of a shade-cloth roll and having a fixed gear, of a revolving member mounted on said hub, cloth-trimming knives carried by said member, a stick-trimming saw, a support therefor provided on said revolving member, a gear mechanism connecting said saw and said fixed gear and arranged to be disconnected from said fixed gear to render said saw inoperative, and means for holding said support and saw in a retracted position when not in use.
18. The combination, with a hub or barrel adapted to receive the end of a shade-cloth roll and having a fixed gear, of a revolving member mounted on said hub, cloth-trimming knives carried by said member, a shaft mounted in said member near the circumference thereof and having a pinion to engage the teeth of said gear, a stick-trimming saw, and driving connections provided between said saw and said shaft.
19. In a shade-cloth trimmer, a member adapted to receive the end of a roll, in combination with cloth-trimming knives, and a stick-trimming saw.

In witness whereof I have hereunto set my hand this 5th day of December, 1902.

FRANK McDANIELS.

In presence of—

RICHARD PAUL,
M. C. NOONAN.
